UNITED STATES PATENT OFFICE.

CHARLES F. RUBEL, OF CHICAGO, ILLINOIS, ASSIGNOR TO UNION SPECIAL MACHINE COMPANY, OF CHICAGO, ILLINOIS, A CORPORATION OF ILLINOIS.

STITCH-FORMING MECHANISM FOR SEWING MACHINES.

Application filed January 29, 1927. Serial No. 164,508.

The invention relates to new and useful improvements in stitch forming mechanism for sewing machines, and more particularly to a thread laying mechanism for a multiple 5 needle covering stitch forming mechanism.

An object of the invention is to provide a covering thread laying mechanism for a multiple needle machine having one needle point set higher than another needle point, 10 wherein the needle with the lowest set point cooperates with the covering thread laying mechanism in the positioning of the covering thread so as to be secured to the fabric by the needle thread loops.

Another object of the invention is to provide a thread laying mechanism wherein the covering thread is laid in loop form through the aid of a movable thread guide and a co-operating thread hook, wherein said hook 20 and guide are so positioned and timed as to carry the covering thread against one of said needles, and in rear of another of said needles, said needles being set at different heights to permit the covering thread to be 25 laid as stated.

A further object of the invention is to provide a covering thread laying mechanism including an oscillating thread guide and an oscillating thread hook which are mounted to swing in opposite directions about independent vertical axes, which hook and guide are oscillated by a single vertical shaft, and wherein the vertical shaft is oscillated by a horizontal shaft receiving 35 its oscillations from the main shaft.

A still further object of the invention is to provide a covering thread laying mechanism of the above type, wherein the thread hook is mounted to oscillate about a vertical 40 axis located in rear of the vertical axis of the thread guide.

These and other objects will in part be obvious and will in part be hereinafter more fully disclosed.

In the drawings which show by way of illustration one embodiment of the invention—

Figure 1 is a front view showing a portion of the machine embodying my improvement;

Fig. 2 is a view showing in end view, the mechanism at the free end of the overhanging arm, and in side view, a portion of the work supporting arm;

Fig. 3 is a view partly in section and

partly in elevation from the rear of the 55 machine;

Fig. 4 is a detail showing the stitch forming mechanism as viewed from in front of the needles;

Fig. 5 is a perspective view of the thread 60 laying mechanism, also showing one of the supporting brackets detached;

Fig. 6 is a sectional view on the line 6, 6 of Fig. 2;

Fig. 7 is a sectional view on the line 7, 7 65 of Fig. 2;

Fig. 8 is a view similar to Fig. 7, with the thread hook and thread guide moved to the other ends of their strokes;

Fig. 9 is a detail showing the arrangement of the needles, the thread guide and the thread hook, and diagrammatically, the seam 70 formed thereby;

Fig. 10 is a diagrammatic enlarged plan view of the seam; and

Fig. 11 is a diagrammatic view showing the needles, the material, the covering thread guide, and the covering thread hook at the time when the strand of the loop in the covering thread is laid against one of the 80 needles.

The invention is directed broadly to a covering thread laying mechanism for a sewing machine. The machine includes a plurality of needles, preferably three, a single 85 looper which cooperates with the needles beneath the work support, and a covering thread laying mechanism which cooperates with the needles above the work support. The needle points are set at different heights, 90 with the needle, the loop of which is first entered by a looper, set the highest. The machine may be further provided with a trimming mechanism, if the machine is used for operating upon knit goods, so that the 95 edges of the fabrics being joined and covered, may be trimmed. The machine may also be provided with means for lapping the fabric sections after they are trimmed and prior to the stitching thereof, the lapping 100 of the sections being within the limits of the covering stitches. The invention is directed particularly to this covering thread laying mechanism which includes an oscillating hook and an oscillating thread guide mounted to oscillate about independent vertical axes. The thread hook and thread

guide are so positioned and timed, that the 105

hook forms a loop in the covering thread, and as it moves to the inner end of its stroke, the thread guide also moves to the inner end of its stroke, and the thread between the eye 5 and the hook is carried against the needle having the lowermost point, engaging said needle somewhere in the region of the eye. The covering thread may also be carried against the middle needle, if three needles 10 are used, depending upon whether the needle is set sufficiently low to be engaged by a covering thread, or sufficiently high, so that the covering thread will pass beneath the same. The needle with the highest set point is set 15 sufficiently high so that this strand of the covering thread loop between the hook and the thread guide is carried in rear of said needle. This forms a loop in the covering thread which is entered by 20 the needle point which is lowest set, and also by the middle needle, if the point is set sufficiently low as to be engaged by the said strand of covering thread. The thread hook and thread guide for the covering thread 25 are both oscillated by a vertical shaft which carries arms projecting in opposite directions, and one arm is connected to the hook, while the other is connected to the thread guide. The respective connections 30 between these arms, and the hook and the guide are such that the hook and guide will be moved in opposite directions; that is, toward each other or away from each other upon an oscillation of the vertical actuating 35 shaft therefor. This vertical actuating shaft may be operated in any suitable way, depending upon the character or type of machine in which the improved covering thread laying mechanism is employed.

40 Referring more in detail to the drawings, I have shown my improved covering thread laying mechanism as applied to a feed-off-the-arm machine designed particularly for stitching tubular work. I have also shown 45 this type of machine as equipped with a trimming mechanism and a differential feed for operating upon knit goods. It is to be understood, however, that the invention may be used in other types of machines; as for 50 example, a flat bed machine, and it is also adapted to be used for forming covering stitches in woven materials as well as in knit materials, and when used in connection with woven materials, a single feed may be used, 55 and the trimming mechanisms dispensed with.

I will now describe the present embodiment of the invention which consists in a 60 work supporting arm 1 which is cylindrical in form, and the material to be stitched is placed around the arm, the edges of the material brought to a meeting line and overlapped, if desired, and then fed off from the end of the arm. Located in this work 65 supporting arm is a feeding mechanism,

which includes a main feed dog 2, and a differential feed dog 3. Also located in this work supporting arm is a thread carrying looper 4. These parts are of the usual construction, and have only been indicated in 70 a very diagrammatic way. The material is held on the work support by a presser foot 5, carried by a presser bar 6. This presser bar 6 is mounted in the free end of an overhanging arm 7. The overhanging 75 arm is carried by a standard 8 in which is located the main operating shaft 9 (see Fig. 3). Also mounted in the overhanging arm 7 is a needle bar 10, which is reciprocated by a needle lever 11 actuated from the main 80 shaft 9. The needle bar 10 carries three needles 12, 13 and 14. The needle 12 is set so that its point is considerably lower than the point of the needle 14, while the central needle 13 is set with its point higher than 85 the point of the needle 12 and lower than the point of the needle 14. This setting of the needle points, one higher than the other, is the usual form or arrangement of the needles where there are a plurality of needles, and 90 a single looper cooperating with all of the needles. The presser foot is provided with a slot 15 leading into the forward end thereof, and a V-shaped rib 16 carried by the work supporting arm cooperates with the slot in 95 directing the edges which are to be joined by the stitching mechanism in an upturned position, so that the edges may be trimmed before they are covered by the stitches. The machine is provided with a trimming mechanism including a stationary trimming blade 17 and a movable trimming blade 18. The movable trimming blade moves across this slot in the presser foot and trims the 100 upturned edge portions of the fabric sections, after which the presser foot is provided with 105 means for turning said trimmed edge portions down into overlapped relation. In Fig. 10 of the drawings, I have shown one 110 of the fabric sections at F, and the other at F'. The presser foot is provided with a needle opening 19 through which the three needles pass.

115 The movable trimming blade 18 is carried by an arm 20, which in turn, is carried by a yoke 21 mounted to oscillate about the presser bar 6. The upper end of the yoke is engaged by a spring 21' which bears against a collar 22 fixed to the presser bar 6, and this spring yieldingly holds the movable blade in shearing relation to the stationary blade. The yoke is provided with an arm 23 which is connected by means of a link 24 to a crank 25 on a shaft 26 journaled in bearings 27 and 28 at the rear of 120 the machine. This shaft 26 is provided with an arm 29, and a link 30 attached to the arm 29 cooperates with an eccentric member 31 on the main shaft 9. Thus it is that the shaft 26 is oscillated, and when said shaft 125 130

is oscillated, it will oscillate the yoke carrying the movable trimming blade, and this will cause said blade to trim the edge portions of the fabric sections.

5 Associated with the needles is a covering thread laying mechanism which includes an oscillating thread guide 32 and an oscillating thread hook 33. The thread guide 32 is fixed to a lever arm 34. Said lever arm 10 34 has a depending sleeve portion 35, and the thread guide 32 is provided with a vertical shank 36 which is secured in said sleeve portion 35 by set screws 37, 37. The lever arm 34 is secured by a vertical pivot bolt 15 38 to a bracket 38^a, which in turn is secured to the overhanging arm by screws 38^b, 38^c. Mounted in suitable bearings in the overhanging arm and at the rear side of the needle head, is a vertical shaft 39. This 20 vertical shaft is held from endwise movement in said overhanging arm by collars 40 and 41 which are fixed to the vertical shaft 39. The presser foot is provided with a rearwardly extending arm 42 carrying a sleeve 43 which surrounds the lower end of the shaft 39, and freely moves up and down thereon when the presser foot is raised and lowered. This vertical shaft 39 is provided with an 25 arm 44 carrying a ball stud and a link 45 co-operating with said ball stud is connected to the crank 25 on the shaft 26.

The shaft 39 is also provided with an arm 46. A link 47 is pivotally connected to the outer end of the arm 46, and this link 47 is 30 connected at 48 to the lever arm 34 which carries the thread guide 32.

The thread hook 33 is mounted in a lever arm 49. Said lever arm 49 has a depending sleeve 50, and the hook has a vertical shank 40 portion 51 engaging said sleeve and secured therein by set screws 52. This lever arm 49 is secured to the bracket 38^a. Said bracket has an arm 53 extending rearwardly from the bracket 38^a, and a pivot bolt 54 passes 45 through an opening 55 in the lever arm 49 and is threaded into an opening in the outer end of the arm 53. The bracket 38^a has a forwardly projecting arm 56 which is provided with an opening into which the 50 pivot bolt 38 is threaded. The vertical shaft 39 is provided with a second arm 57 which is in alignment with the arm 46, but projects in an opposite direction from the center of the shaft 39. A link 58 is pivoted to the outer end of the arm 57, and is pivoted at 59 to the lever arm 49 which carries the thread hook.

From the above it will be obvious that 55 when the shaft 39 is oscillated, it will oscillate the thread hook 33 through the link connection 58, and will also oscillate the thread guide 32 through the link connection 47. The link 47 is connected to the lever arm 34 at a point intermediate the pivotal point of 60 the lever arm and the thread guide, while

the link 58 is connected to the lever arm 49 at one end thereof, and the pivot point of said lever arm 49 is between this connection to the link and the hook. As a result, when the vertical shaft is oscillated in one direction, the hook will be moved one way and the thread guide will be moved the other way. That is, the thread hook and thread guide will be moved toward each other, and when the shaft is oscillated in the other direction, then the thread hook and thread guide will be moved away from each other.

The covering thread is indicated in the drawings at *c*. The covering thread is led from the supply through suitable guides, and finally to the stationary thread guide 60 carried by the presser foot. The covering thread then passes through a thread guide 61 on the shank of the thread guide, and to the thread guide 32. The thread guide and thread hook are disposed a sufficient distance above the presser foot as to permit the presser foot to be raised and lowered. Said thread guide and thread hook oscillate in fixed planes relative to the needle head on 90 the overhanging arm. The thread of the needle 12 is indicated at *n*, the thread of the needle 13 is indicated at *n'*, and the thread of the needle 14 is indicated at *n''*. The thread guide oscillates from an outer position, as shown in Fig. 7, to an inner position, as shown in Fig. 8. At the same time, the thread hook moves from the outer position, shown in Fig. 7, to the inner position, shown in Fig. 8. As the thread guide and thread hook move to their inner position, the needles are at the upper ends of their strokes, and are descending. The thread guide 32 is so pivoted on its supporting bracket 38^a that the path of movement of the thread guide is from in front of the needles to a position slightly in rear of a vertical plane containing the center of the needles. The thread hook swings in a longer arc, as the pivotal support for the thread hook is in rear of the 105 pivotal support for the thread guide. The thread hook moves in a path, therefore, from in front of the needles to a point substantially terminating in a vertical plane containing the center of the needles. As the thread 110 hook moves to the inner end of its stroke, it engages the covering thread *c*, passing through the thread guide 32 between the thread guide and where the covering thread is interlocked with the stitching threads at 115 the previous stitch. The thread hook, therefore, forms a loop indicated at *c'* in Fig. 9 of the drawings. The strand running between the hook and the thread guide is carried against the needles 12 and 13. As 120 clearly shown in Fig. 4 of the drawings, the needles at this time are at such a position in their path of reciprocation, that the points of the needles 12 and 13 are below the covering thread, while the point of the needle 14 125

130

is well above the covering thread. This is clearly shown in Fig. 11 of the drawings. As will be clear from Fig. 9 of the drawings, the strand of the loop *c'* extending between 5 the hook and the thread guide, and which engages the needles 12 and 13, will be positively held in front of said needles by the needles themselves, while this same strand of the thread loop *c'* is carried in rear of 10 the needle 14. Thus it is that the two needles 12 and 13 enter the thread loop *c'* while the covering thread is laid around the needle 14 and anchored or secured to the fabric preparatory to the forming of the 15 next thread loop in the covering thread. This is an important feature in my invention, as I have provided a covering thread laying mechanism wherein the needles themselves become positive elements in the positioning of the covering thread and in the insuring that the covering thread shall be laid 20 in such a way relative to the needles, as they descend, that certain of the needles will enter the covering thread loop, while the other 25 needle or needles will anchor the covering thread to the fabric. By this arrangement, I am able to lay the covering thread in loop form, for each reciprocation of the needles, and thus fully cover the raw edge of the 30 fabric.

It will readily be seen that if the point of the needle 13 is raised slightly, even though it is not set as high as the point of the needle 14, the covering thread *c* will pass 35 in rear of this needle 13. It is essential that the covering thread shall always be in front of the needle 12, and always be in rear of the needle 14. The position of the covering thread relative to the central needle or 40 needles is immaterial.

From the above it will be apparent that I have provided a covering thread laying mechanism for a sewing machine having a plurality of needles set abreast, which is 45 very simple in construction, and wherein the cooperating covering thread guide and loop forming hook are moved toward each other and away from each other by a single actuating shaft, and wherein the needles are 50 so set, and the hook and guide are so positioned and timed, that the strand in the covering thread loop which is anchored to the previously formed stitches, is laid in rear of the path of the needles, while the 55 strand extending between the hook and the guide for the covering thread is laid against the needle nearest the hook, and the strand thereby deflected in its course between the hook and the guide so that said strand is 60 laid with certainty in rear of the path of the needle nearest the guide.

While I have shown my improved covering thread laying mechanism as embodied 65 in a machine for forming tubular articles, from knit material, it will be understood, as

has already been noted, that the covering thread laying mechanism may be used in other types of machines without departing from the spirit of the invention as set forth in the appended claims. 70

Having thus described the invention, what I claim as new and desire to secure by Letters-Patent, is—

1. The combination of a plurality of needles; of a covering thread laying mechanism cooperating therewith and including an oscillating covering thread guide and an oscillating hook, a lever arm fulcrumed at its end carrying said guide, a lever arm fulcrumed intermediate its ends and carrying said hook, a vertically arranged actuating shaft, arms projecting in opposite directions therefrom, a link connecting one of said arms with the end of the lever arm carrying the hook, and a link connecting the other arm with the lever arm carrying the guide intermediate the fulcrum therefor and the guide, and means for actuating said vertical shaft. 75

2. The combination of a plurality of needles; of a covering thread laying mechanism cooperating therewith and including an oscillating covering thread guide and an oscillating hook, a lever arm fulcrumed at its end carrying said guide, a lever arm fulcrumed intermediate its ends and carrying said hook, a vertically arranged actuating shaft, arms projecting in opposite directions therefrom, a link connecting one of said arms with the end of the lever arm carrying the hook, a link connecting the other arm with the lever arm carrying the guide intermediate the fulcrum therefor, and the guide, and means for actuating said vertical shaft, said last-named means including a horizontally disposed shaft, a crank arm carried thereby, an arm on the vertical shaft, and a link connecting said last-named arm to the crank arm on the horizontal shaft. 100

3. The combination with three needles set abreast and having the point of the needle at one side of the seam lower than the point of the needle at the other side of the seam, of a covering thread laying mechanism including devices positioned and timed for forming a loop in a covering thread and placing the strand of said loop running to the supply against the side face of the needle with the lowest set point and subsequently placing said strand running to the supply beneath the point of the needle at the other side of the same and in rear of the path thereof, whereby the needle with the lowest set point enters the loop formed in the covering thread and the covering thread is anchored to the fabric preparatory to the forming of another loop therein. 115

4. The combination with three needles set abreast and having the point of the needle 120

at one side of the seam lower than the point of the needle at the other side of the seam, of a covering thread laying mechanism including a covering thread guide oscillating from a position at one side of said needles to a position at the other side thereof and in a path in front of the needles, a hook cooperating with the guide and oscillating from one side of said needles to the other side thereof and in a path in front of said needles said needles being set so that the point of the needles nearest the hook when the loop is formed is lower than the point of the needle nearest the thread guide at this time, said guide and hook being so posi-

tioned and timed that a loop is formed in the covering thread and the strand running from the hook to the guide placed against the side face of the needle with the lowest set point and subsequently moved beneath the point and in rear of the path of the needle with the highest set point, whereby the needle with the lowest set point enters the loop formed in the covering thread and the covering thread is anchored to the fabric preparatory to the forming of another loop therein.

In testimony whereof, I affix my signature.

CHARLES F. RUBEL.
